FIG. 1

FIG. 2

FIG. 3

FIGURE 1 is a perspective view of a cooking stove showing my new design and showing particularly the front of the stove and one side thereof.

FIGURE 2 is a side elevation view of the stove of FIGURE 1, and

FIGURE 3 is an enlarged fragmentary sectional view taken on line 3—3 of FIGURE 1 and looking in the direction of the arrows.

The other side of the cooking stove is similar to the side shown and the rear and bottom of the range not illustrated, are plain.

I claim:

The ornamental design for a cooking stove, as shown and described.
